PROCESS FOR REDUCING THE SULPHUR
CONTENT OF GASOLINE

Victor Abeles, Nashville, Tenn.

Application February 4, 1943, Serial No. 474,659

4 Claims. (Cl. 196—29)

This invention is a new and useful process for reducing the sulphur content of a light hydrocarbon distillate such as naphtha or gasoline produced, for example, by distillation from a crude petroleum. The invention will be fully understood from the following description read in conjunction with the drawing which is a diagrammatic plan of apparatus in which the invention may be carried into effect.

Referring to the drawing, 1 indicates a pipe still, including inlet 2 communicating with heater coil 3, discharging through outlet 4. The coil 3 is housed in a suitable refractory setting 5 heated by burner 6, the products of combustion passing off through stack 7.

Outlet 4 discharges into 11 which is a rectifying column. This column is provided with a discharge outlet 12 through which bottoms may be withdrawn, with a side outlet 13 through which a cut in vapor phase may be withdrawn; with a side outlet 14 through which a lower boiling cut in vapor phase may be withdrawn and with an outlet 15 adjacent the upper part of the column through which the lowest boiling cut may be withdrawn in vapor phase.

The column 11 is equipped with the usual liquid-vapor counter current contacting devices (not shown). It is preferably equipped with a reflux condenser (not shown) adjacent the upper part thereof and may have a reboiler coil adjacent the lower part thereof.

Vapors from the outlet 15 pass into heat exchanger 16 in which they move in indirect heat-exchanging relationship with a liquid which is introduced through inlet 17, passing off through outlet 18. The condensate resulting from the condensation of the vapors passes off through outlet 19.

Outlet 19 communicates with separator 20, the function of which is to separate any water present in the condensate. This water passes off from the separator through the bottom outlet 20', while the water free condensate is discharged through pipe 20'' into the lower section of tower 21. This tower is equipped with liquid-liquid countercurrent contacting devices (not shown). A heavier treating liquid may be introduced through side arm 22 and after passing downwardly in countercurrent contact with a lighter ascending liquid is withdrawn through bottom outlet 23. The lighter liquid that has been treated passes off through outlet 24, adjacent the upper part of the tower.

The outlet 24 discharges into the intermediate section of the tower 21. This tower has a bottom

inlet 32 through which a gas may be introduced passing upwardly through foraminous partition 33 by which it is resolved into fine bubbles which commingle with any liquid in the space 34 above the partition. Above the space 34 is a horizontal grate or partition 35 upon which is supported a solid contact material 36 through which the liquid may pass upwardly passing out of the apparatus through side arm 37. Any excess or unabsorbed gas will escape through upper outlet 38. The liquid from side arm 37 may be returned through valved pipe 39 into the upper part of column 11 or may be diverted in whole or in part out of the system through valved pipe 40.

In the operation of the apparatus, a crude petroleum containing light hydrocarbons such as naphtha or gasoline hydrocarbons and higher boiling hydrocarbons is introduced continuously to pipe still 1 through inlet 2. Such oils normally also contain organic sulphur bearing compounds, such as, mercaptans, some of which boil within the naphtha or gasoline range and are therefore responsible at least in part for the sulphur content of any gasoline derived from such crudes.

The crude petroleum so introduced is heated in heater coil 3 to substantial vaporization or to substantially complete vaporization and in this condition is discharged through outlet 4 into the lower part of rectifying column 11 within which is maintained a rectifying zone. Heavy ends or bottoms are taken off continuously through bottom outlet 12. A distillate such as gas oil is taken off in vapor phase through side outlet 13. A lower boiling distillate such as kerosene is taken off in vapor phase through side outlet 14. The lowest boiling cut, i. e., the gasoline or gasoline and naphtha is taken off in vapor phase through upper outlet 15. In heat exchanger 16 this cut is condensed to liquid phase. It is then run through the separator diagrammatically indicated by 20 in which it is freed of any water. The water is withdrawn from the system through the bottom outlet 20', while the water free condensate is discharged through the side outlet 20'' into the lower section of tower 21.

Concentrated caustic solution is introduced through side inlet 22 and after passing downwardly in counter current contact with the ascending gasoline is withdrawn, through bottom outlet 23. The effect of the caustic is to remove sulphur reactive therewith, such as hydrogen sulfide and some mercaptans and the gasoline or mixture of gasoline and naphtha freed of these passes off through the upper outlet 24.

This cut is discharged into the lower section

of tower 31. Oxygen which may be in the form of air, but is preferably substantially pure is introduced through inlet 32 and is resolved by foraminous partition 33 into a multitude of fine bubbles which commingle with and, to an extent at least, dissolve in the gasoline or mixture of gasoline and naphtha in space 34. The cut then passes up through the foraminous partition or grate 35 into the space above the same. This space contains a cupric salt. This may, for example, be cupric chloride or any of the commercially available metallic compounds which have the same chemical affinity towards mercaptans and other forms of organic sulphur. These compounds react with the mercaptans present, while the oxygen operates to regenerate the metallic compounds simultaneously converting the mercaptans into a form less odorous, negative to the doctor test and therefore less objectionable.

While I prefer this particular, known, sweetening method in association with the other steps that characterize my invention, it will be understood that I am not limited thereto and may in fact employ at this point any of the recognized sweetening reagents. I may, for example, use at this point a sodium plumbite solution; in this case the amount of added elemental sulphur should not in any event exceed that present in mercaptan form in the gasoline.

On starting up the system the reflux condenser in the upper part of column 11 is operated and all of the sweetened gasoline or gasoline and naphtha from outlet 37 is returned through valved pipe 39 into the upper part of column 11. Being in liquid phase it will function as reflux and as it builds up in the system the reflux condenser may be progressively throttled until this gasoline is returning in sufficient amount to provide all the reflux required in column 11. Thereupon, the valve in pipe 40 is opened and an amount of gasoline or gasoline and naphtha corresponding to that present in the crude oil coming into the system is withdrawn through pipe 40. The amount of gasoline or gasoline and naphtha continuously recycled through pipe 39 should be at least equal in amount to that contemporaneously withdrawn through pipe 40 and for best results should be at least three times that amount. In a specific case in which it was four times that of the gasoline withdrawn through pipe 40, the amount of sulphur present in the finished gasoline withdrawn from the system was reduced to a minor percentage of that present in the finished gasoline under otherwise identical conditions with the usual once through process.

It will be understood that I may similarly treat any cut taken off from the rectifying zone even though it is not the cut of lowest boiling point. In this case the sweetened and recycled cut will be re-introduced into the rectifying zone in liquid

phase at or below the level at which it was taken off. The cut or cuts of lower boiling point simultaneously taken off from the rectifying zone may, if desired, be simultaneously similarly treated.

5 In any case a cut or bottoms of higher boiling point than that sweetened, in accordance with my process, will be simultaneously taken from the rectifying zone.

The foregoing description is for purposes of illustration and not of limitation and it is therefore my intention that the invention be limited only by the following claims or their equivalents wherein I have endeavored to claim broadly all inherent novelty.

I claim:

1. Process of producing petroleum distillate of reduced sulphur content from a mixture of hydrocarbons containing mercaptans boiling within the same range which comprises continuously introducing such a mixture into a rectifying zone, taking off from said rectifying zone a petroleum distillate and at least one higher boiling fraction, thereafter treating said distillate in liquid phase with a sweetening agent

20 in amount sufficient to react with the mercaptans contained therein, continuously abstracting from the process an amount of treated distillate corresponding to the distillate contained in the said mixture contemporaneously coming into said rectifying zone and recycling at least a part of the remainder of said distillate into said rectifying zone, the amount of distillate so recycled being at least equal to that abstracted.

25 3. Process according to claim 1 in which the sweetening agent includes cupric chloride and free oxygen.

40 4. Process of producing petroleum distillate of reduced sulphur content from a mixture of hydrocarbons containing mercaptans boiling within the same range which comprises continuously introducing such a mixture into a rectifying zone, taking off from said rectifying zone a petroleum distillate and at least one higher boiling fraction, thereafter treating said

45 distillate in liquid phase with a sweetening agent in amount sufficient to react with the mercaptans contained therein, continuously abstracting from the process an amount of treated distillate corresponding to the distillate contained in the said mixture contemporaneously coming into said rectifying zone and recycling at least a part of the remainder of said distillate into said rectifying zone the amount of distillate so recycled being at least three times that abstracted.

50 5. Process according to claim 3 in which the sweetening agent includes cupric chloride and free oxygen.

55 60 VICTOR ABELES.
